REMOVABLE LADDER STEP

Adolph Voigt, Miami, Fla.

Application October 24, 1936, Serial No. 107,453

2 Claims. (Cl. 228—60)

This invention relates to removable steps adapted for use on stepladders, and more particularly to removable ladder steps that are inexpensive in construction, and readily adapted to use with ladders to be placed in any desired position thereon.

Among the objects of the present invention is the construction of a ladder step of any desired material, that may be inexpensively constructed and simply applied in use on ladders, enabling ready removal of the ladder step from and into the desired position.

Other objects and advantages will appear from the more detailed description set forth below, it being understood, however, that this more detailed description is given by way of illustration and explanation only, and not by way of limitation, since various changes therein may be made by those skilled in the art without departing from the scope and spirit of the present invention.

In accordance with that more detailed description, there is shown by way of illustration in the accompanying drawing, in

Figure 1, a front elevation of a ladder carrying removable step members in accordance with the present invention, two such step members being shown, one of them in cross section, in position on said ladder; in

Figures 2 and 3, side elevations of ladders carrying the step members as shown in Figure 1, portions of the ladder and lower step members being shown in section; in

Figure 4, a plan view of a removable step member made in accordance with the present invention, in position on the ladder of Figure 1, the rails of the ladder being shown in section, the section being taken on the line 4—4 of Figure 1; in

Figure 5, a perspective view of one of the extension members of the step shown in Figures 1—4; in

Figure 6, a modified form of step of the present invention shown in position on a ladder; in

Figure 7, a side elevation of the ladder of Figure 6 showing the step in position, the view being partly in section; and in

Figure 8, a plan view of the step in position on the ladder taken along the line 8—8 of Figure 6.

In accordance with the present invention, a removable step member is produced for use on any desired type of ladder, although as illustrated in the drawing, the invention is particularly useful in connection with those ladders having substantially square-type rails provided

with rounded rungs. While the invention is capable of use with any type of ladder, it is particularly useful in connection with the type of ladder shown in the drawing, since in the use of ladders with rounded rungs, insufficient support is given for the foot, and continued use of such ladders and continued standing on the rounded rungs results in substantial strain. The removable steps of the present invention are particularly useful in connection with ladders of this type to relieve any strain in their long continued use. In illustrating the invention, and as shown in the drawing, two steps are shown on each of the ladders, but this is for the purpose of illustrating certain features in connection with the steps, since although any number of such step members can be applied to ladders, it is unnecessary to use more than a single step member, which is applied to the rung at the particular place where the user of the ladder must stand for some substantial period of time.

The particular type of step member produced in accordance with the present invention, is a step member which can be readily applied to the desired ladder, the step member being a substantially flat article, the ends of which are cut away to receive the rails of the ladder. Such steps may be made either extensible, as shown in Figures 1—5, or substantially of one piece as shown in Figures 6 to 7. The extensible type steps are desirably made of metal, while the one-piece step, as shown in Figures 6 to 8, may desirably be made of wood, although wood members may be telescoped to provide the form of device shown in Figures 1 to 5, if desired, while single metal steps of the form shown in Figures 6 to 8 may also be employed.

Considering more particularly the extensible form of step as shown in Figures 1—5, the ladder L having the usual rails 1, 2 is provided with the usual rungs 3. The step S produced in accordance with the present invention is desirably made of two telescoping members 4, 5, the exposed ends of each of these telescoping members 4, 5 being provided with a cut-out portion 6, 7, respectively, for receiving the rails 1, 2 of the ladder. When such extensible members 5 are produced of sheet metal, as illustrated, those portions of the metal which are cut away to produce the rail reception openings 6, 7 may desirably be bent downwardly, as particularly shown in Figure 5, to provide tongues 8 and 9 on one member and 10 and 11 on the other, which metal tongues serve the purpose of gripping the sides of the rails 1, 2 of the ladder. While not essential, such

- tongues 8, 9, 10, and 11 are desirable in gripping the sides of the rails 1 and 2, and holding the step in position. The step rests on the corresponding rung 3 adjacent thereto, and even though the vertical angle at which the ladder is employed may vary as shown in Figures 2 and 3 particularly, due to the configuration of the rail-receiving-cutaway portions of the step members and the depending gripping tongues 8, 9, 10, and 11, the step will shift to a horizontal position regardless of the angle at which the ladder is used, as particularly shown in Figures 2 and 3, the step in all cases being retained in a substantially rigid position.
- 15 When made of sheet metal, the telescoping members may be held together in any desired way, but as shown in the drawing, this is desirably accomplished by rolling the edges of each of the extensible members 4, 5 to produce channel portions 12 and 13 on the inner telescoping member, and channel members 14 and 15 on the outer telescoping member, these channel members lying within each other and serving to hold the step portions together.
- 25 In the extensible form of step shown in Figures 1-5, the step is easily placed in position by telescoping the members until the width of the step is considerably less than that of the ladder, and then placing the step on the particular rung of the ladder desired, followed by extension of the step members until the rail-receiving portions of the step members are positioned about the rails, with the tongue portions 8, 9, 10 and 11 serving to hold the step in position on the particular rung.
- 35 In a similar manner the step may be removed from any particular rung, and either taken away completely from the ladder, or placed on any other rung thereof.

In the form of the device shown in Figures 6 to 8, a substantially one-piece step is shown. In this form, the ladder L having rails 1 and 2 and rungs 3 is provided with a one-piece step 20, desirably made of wood, and having a width greater than the distance between the rails of the ladder, but less than the diagonal distance between successive rungs of the ladder, so that the step may be raised into an angular position and removed from

between the rails. Each of the ends of the step 20 is provided with a cut-out portion 21 adapted to receive the rails 1 and 2 of the ladder.

In using the single piece step shown in Figures 6 to 8, the step may be placed in position on any particular rung by inserting the step diagonally between the rungs, with one of the rail receiving cut-out portions 21 positioned against the corresponding rail, and then dropping the step into horizontal position, so that the other rail receiving cut-out portion 21 is placed about the corresponding rail. The step will occupy the position shown of each of the steps in Figures 6 and 7. Similarly, the step may be removed from such position by reversal of the procedure just mentioned.

It will be seen that a simple step is provided, either of one piece or telescoping members that may be economically constructed, of inexpensive materials, and simply applied in connection with any desired type of ladder and used, as desired, on any rung thereof.

Having thus set forth my invention, I claim:

1. A removable ladder step adapted to rest on the rung of a ladder, said step comprising telescoping members extensible to a width greater than the distance between the rails of the ladder, the end portion of each telescoping member being cut away to receive the corresponding rail, the cut away portion of the extensible members having a pair of tongues lying within the cut-away portion and formed from the metal that is cut away for gripping the corresponding rail, said tongues being directed downwardly and toward each other so that they serve to maintain the step in a substantially horizontal position.

2. A removable ladder step having a substantially flat main body portion adapted to rest on the rung of a ladder and having cut away parts in its end portions adapted to receive the corresponding rail, the cut away part of each end portion having a pair of tongues for gripping the corresponding rail, said tongues being directed downwardly and toward each other so that they serve to maintain the face of the main body portion in a substantially horizontal position.

ADOLPH VOIGT.
